JACOB H. HIRSCH, OF ATLANTA, GEORGIA, ASSIGNEE TO HIRSCH & SPITZ MANUFACTURING CO., OF ATLANTA, GEORGIA, A CORPORATION OF GEORGIA.

SPRING BED-BOTTOM.

1,135,797.

Specification of Letters Patent. Patented Apr. 13, 1915.

Application filed November 10, 1913. Serial No. 800,144.

To all whom it may concern:

Be it known that I, JACOB H. HIRSCH, a citizen of the United States, residing at Atlanta, in the county of Fulton and State 5 of Georgia, have invented new and useful Improvements in Spring Bed-Bottoms, of which the following is a specification.

This invention relates to improvements in spring bed-bottoms and consists in certain 10 peculiarities in the construction and arrangement of parts, and in certain novel combinations of elements substantially as hereinafter described and particularly pointed out in the subjoined claims.

More especially the invention relates to 15 a fabric which is composed in part of helically coiled springs from which the resiliency of the fabric is obtained and in part of a new combination of members of different 20 though related shapes and not essentially of spring or resilient character, the said members being so constructed and combined or correlated that the mesh will be composed of substantially diamond-shaped sections 25 formed in a simple, practicable and economical way, with a view of producing a fabric which will readily yield to weight, will possess maximum strength, will retain its shape and may be economically manufactured, and one in which any strain imposed 30 on any part thereof will be transmitted throughout a maximum area.

In the accompanying drawings, wherein 35 like characters of reference denote corresponding parts in the several views, I have illustrated the preferred embodiment of the present invention, but it should be understood that changes in the details of construction may be made without departing 40 from the spirit of the invention or the scope of the subjoined claims.

In said drawings:—Figure 1 is a plan view of a link spring bed bottom constructed in accordance with the present invention, 45 showing an end of the upper web or flange of one transverse frame member and the vertical part of said member in section to disclose a desirable way of connecting the corner riser or support thereto. Fig. 2 is 50 a detail side elevation of one corner of the frame; and Fig. 3 is a vertical sectional view of the latter.

The frame comprises two longitudinal side members, A, A', and transverse end 55 members B, B'. the transverse members

being supported from the longitudinal members in a plane higher than the latter by corner brackets or risers each of which is marked C. Each longitudinal frame-member is preferably of tubular form and each transverse member is preferably of angle-form. Each corner riser or bracket has a suitable part, as the sleeve 10 for example, by which it is connected to or mounted upon the end of a longitudinal member A, A', and also has an outwardly and upwardly curved part 11 whose upper end is provided with a flange 12 against which the adjacent transverse member B or B' rests. Each corner bracket or riser further has an outwardly projecting lateral lug 13. These lugs support the bed bottom from the side rails of the bedstead, as is usual.

In order to prevent axial movement of the corner brackets or risers upon the 75 rounded surfaces of the longitudinal members A, A', the latter are formed with apertures 14 and the corner brackets or risers have inward projections 15 arranged to be seated in said apertures. 80

The transverse members B are secured to the flanges 12 of the corner brackets or risers by the lugs 16 projecting from the latter into apertures 17 formed in the transverse members, said lugs being preferably 85 of such nature that after they have been inserted in the apertures 17 their outer ends may readily be upset, by a hammer or other appropriate tool, to prevent separation of the transverse members B therefrom. 90

The described construction of frame is one which I prefer but it will be understood that changes therein may be made without departing from the spirit of my invention, the features of the bed bottom with which my 95 invention is particularly concerned being in the fabric, including therewith, or as a part thereof, the means for connecting the same or the mesh part thereof with the frame.

The fabric comprises a mesh portion which 100 is composed of a series of transverse members D, each of which extends continuously across the fabric: a transverse member E at one end thereof, this similarly extending continuously entirely across the fabric: a series 105 of V-shaped members F at the other end of the fabric: and a series of lines of diagonally arranged links G, some of which (G) connect the transverse members D with each other and others of which (G') connect one 110

transverse member D with the transverse member E, the transverse members D being spaced apart along the length of the fabric and the one nearest the member E being spaced from the latter.

Each of the transverse members D is formed of a wire of suitable character bent to form two outwardly extending arms 20, 20 at the ends thereof, a series of alternating arms 21 and 22, arranged diagonally—respectively extending toward the right and left—and lateral elements 23 and 24 arranged between the arms and connecting their ends to each other, the elements 23 being arranged in line with the outwardly-extending ends 20 and the elements 24 being arranged at the opposite ends of the arms. The ends of each connecting element 23 and 24 at their junctions with the arms 21 and 22 are offset to form two seats 25 and 26 for a purpose which will hereinafter appear. Other seats 27 are formed at the junctions of the outside arms 21 and 22 respectively with the ends 20. It will be noted that a transverse member D thus formed presents a series of spaced-apart sections each composed of arms 21 and 22 and a lateral connection 24, arranged alternately with a like series of spaced apart sections, composed of the same arms 21 and 22 and a lateral connection 23. It will further be noted that the relative arrangement of the transverse members D is such that in the completed fabric the first-mentioned sections are arranged in lines with each other longitudinally of the fabric—there being a series of such lines corresponding to the number of said sections in each transverse member, as is apparent—and that the second mentioned sections (e. g. those formed of the side arms 21, 22 and the lateral elements 23) bear a like relation to each other.

The members D are connected to each other by the intermediate links G whose ends are of hooked formation and are arranged in the seats at the closed ends of the sections formed by the arms 21 and 22 and the lateral connecting elements 23 and 24. Each transverse line of said links is composed of a series of links extending alternately toward the right and left—those which extend toward the left being interposed between the arms 21 of two members D while those which extend toward the right similarly are interposed between the arms 22 of said members. The meshes thus formed of the members D and G are of approximate diamond shape, as will be seen.

The member E forming one end of the fabric differs from the members D in that each pair of its alternating arms, marked 31 and 32, converge to a point at one end, marked 34. These points, which form apices of V-shaped sections, take the place of the lateral bends 24 in the members D and serve

as means whereby the members E may be connected to a line of helically coiled springs H by which one end of the fabric is yieldably supported from the contiguous transverse frame-member B. In other respects the member E is like each member D, its V-shaped sections being connected to each other by lateral elements 33 each of which is bent to form seats 35 and 36 at the junctions of its ends with the arms 32 and 31 respectively of the V-shaped sections of the member, and said member also terminating at each end in an outwardly-extending arm 30 each having a bend 37, the said bends 37 forming seats at the junctions of the arms 30 with the adjacent side arms 31 and 32 respectively of the V-shaped sections at the ends of the member E. The member D at this end of the fabric is connected to the element E by a line of diagonally-arranged links G', the said links extending alternately to the right and left as hereinbefore described.

The members F, which are arranged at the other end of the fabric, are each separate from every other and each is approximately V-shaped, being composed of two converging arms 41 and 42. Their closed ends or apices 43 are engaged by helically coiled springs H' by which this end of the fabric is yieldably supported from the transverse frame member B'. The free ends of the outer arms 41 and 42, respectively, of the outer members F are hooked into the seats 27 formed by the bends at the junction of the outer laterally-extending ends 20 and adjacent diagonal arms of the adjacent member D. All the other arms of said members F are hooked over the bends 25 and 26 at the junctions of the lateral elements 23 and diagonal arms 21 and 22 of said member D. The diamond-shape of the mesh is thus continued to, or retained at, this end as well as at the other end and throughout the body of the fabric.

The outwardly-extending arms 20 of the members D and the like ends 30 of the members E are suitably engaged with appropriate edging members I I' which extend longitudinally of the bed-bottom and have their ends connected to the transverse frame members B B' by the helical springs J J'. These longitudinal members preferably consist of flat strips, as shown, having apertures to receive the ends of the arms 20 and 30, the ends of the latter being preferably of hook-form to retain them in engagement with the longitudinal members. These longitudinal members serve as edging strips for the mesh portion of the fabric, enabling the bottom to sustain any strain which is placed upon its edge without permanent deformation thereof, and they also prevent permanent deformation of the interior meshes of the fabric from use.

Having now described the invention what I believe to be new and desire to secure by Letters Patent, and therefore claim, is:

1. In a spring bed bottom, a fabric having longitudinal edging members, a series of spaced transverse members each extending continuously across the fabric and having its ends secured to the edging members and being bent between its ends to form a series of spaced diagonal arms extending alternately toward opposite edges of the fabric with lateral sections connecting said arms with each other, and diagonally arranged links connecting the transverse members with each other, said links extending alternately toward opposite edges of the fabric and being so arranged with relation to the transverse members that the meshes formed by the links and transverse members 20 will be approximately diamond-shaped.
2. In a spring bed bottom, a fabric comprising a mesh portion having a series of transverse members each of which extends continuously across the fabric and is formed with outwardly extending arms at its ends and between said arms with a series of spaced diagonal arms extending alternately toward opposite edges of the fabric and lateral sections connecting the diagonal arms 25 with each other, the mesh portion also comprising diagonally-arranged links whose ends are connected to the transverse members adjacent to the junctions of the lateral sections and outwardly extending arms respectively with the diagonal arms, the said links extending alternately toward opposite edges of the fabric and being so arranged with relation to the transverse members that the meshes formed by the links and trans- 30 verse members will be approximately diamond-shaped; and longitudinal edging members connected to the outwardly extending arms at the ends of the transverse members.

3. In a spring bed bottom, a fabric having a series of transverse members each of which extends continuously across the fabric and is bent to provide laterally extending arms at the ends thereof, spaced diagonal arms extending alternately toward opposite edges of the fabric and laterally extending connecting elements between said diagonal arms, said transverse members being spaced apart; links connecting them to each other and correlated therewith so as to form meshes which are approximately diamond-shaped: the fabric also having one of its ends formed of separate approximately V-shaped links, the free ends of whose arms are connected to the adjacent transverse member and are correlated therewith to form diamond-shaped meshes, the fabric, further, having at its other end a transverse member extending continuously across the fabric and bent to form a series of approximately V-shaped sections with lateral connecting elements between said sections and laterally extending arms at the ends, diagonally arranged links connecting the last named transverse member with the adjacent transverse member and said members and links being correlated to form meshes of approximate diamond shape: longitudinal edging members connected to the outwardly extending arms at the ends of the transverse members: springs arranged to connect the ends of said edging members with the ends of the frame of the bottom and other springs arranged to connect the end meshes of the fabric to said frame. 45 50 55 60 65 70 75 80

In testimony whereof I have hereunto set my hand in presence of two subscribing witnesses.
